UNITED STATES PATENT OFFICE.

BELTON T. HAMILTON, OF LONDON, ENGLAND.

AEROPLANE.

1,106,804.

Specification of Letters Patent. Patented Aug. 11, 1914.

Application filed April 25, 1912. Serial No. 693,198.

To all whom it may concern:

Be it known that I, BELTON TATTNALL HAMILTON, a subject of the King of Great Britain, residing at Euston Buildings, 5 George street, Euston Road, London, N. W., England, have invented certain new and useful Improvements in or relating to Aeroplanes, of which the following is a specification.

10 This invention relates to improvements in aeroplanes and its chief object is to provide an aeroplane having automatic stabilizing or balancing means while at the same time permitting the aviator to control the aeroplane at will both as regards stabilizing and balancing and otherwise.

Combined automatic and manual stabilizing means have been devised in which the automatic stabilizing action is obtained by 20 suitably connecting together various portions of the planes so that an excess pressure on one portion modifies the other portion and in which the automatic action can be overcome at the will of the aviator by 25 manipulating a control wheel or lever. These devices have, however, hitherto been open to the objection that the manual control wheel or lever is operated by the automatic stabilizing action when the stability 30 is not being maintained manually. This arrangement is obviously open to many objections, the chief of which is that if the automatic stabilizing action is to act properly, the aviator must release his hold of the 35 wheel or lever which must then be free to move about as determined by the action of the automatic stabilizing means.

Now according to the present invention in an aeroplane the two sides of a simple or 40 compound plane or two portions of said sides are so connected together that they are automatically deflected in opposite directions while the connection is such that the sides of the plane or portions thereof 45 may, when desired, be deflected in opposite directions at will, by moving a lever, hand wheel or the like in either direction from its neutral or mid-position, the said lever or hand wheel when in mid-position in no way 50 interfering with the automatic stabilizing action, thus enabling the aviator to maintain his hold on the wheel at all times, so as to be ready to instantly assume control when desired. A further advantage is that the 55 aviator, while not interfering with the automatic stabilizing action, can, by manipula-

tion of the wheel or lever or accessory parts thereof, control other portions of the aeroplane, such as the engines, rudder, etc.

Another feature of this invention is the 60 means whereby the deflection of the two sides or portions thereof can be varied in the same direction at will, and a third feature of the invention is the combination in an aeroplane of means to produce an auxiliary head resistance on one side of the plane with combined automatic and manual or like means for warping the plane of the kind described, for the purpose of equalizing the head resistance on the two sides of 70 the plane.

Other features of this invention will be evident from the following description of one form of aeroplane constructed according to this invention.

Before, however, proceeding to describe this construction it will be as well briefly to review existing practice in the construction and control of aeroplanes. In the first place an aeroplane must be under control in three 80 distinct planes. (1) It must be so controlled as to be able to be held to a vertical plane containing the axis of flight, but must at the same time be capable at the will of the operator of being steered either to the left or right. (2) It must be so controlled as to be able to be held to a horizontal plane containing the axis of flight, but must at the same time be capable of being steered up or down. (3) It must be controllable in a vertical 85 plane at right angles to the axis of flight in such manner as to prevent rolling or capsizing in a sidewise direction, but must at the same time be capable of being tilted sideways at the will of the operator when steering around curves. It is clear that it is 90 greatly desirable that the aeroplane should possess a certain degree of automatic stability tending to keep it to the axis of flight as determined by the operator, and that it 100 should also possess automatic side stability tending to keep it from rolling or capsizing in a sidewise direction. Automatic directional stability in a vertical plane perhaps is not of great importance, and the want of 105 such stability is not a danger. Automatic longitudinal stability in a horizontal plane is more important and is more or less successfully assured by V-ing the fore and aft planes in well known manner. Automatic 110 side stability has not up to the present been successfully accomplished. A certain de-

gree of automatic stability in this direction may be obtained by arranging a dihedral angle between the planes, or by upturning the ends, or by the use of vertical fins, but the righting couple produced by such an arrangement is so small as to be insignificant in comparison with possible and probable upsetting forces.

The types of aeroplanes having fixed wings or fixed form are what may be termed one-spaced machines, that is to say, they will only travel at one fixed speed in a horizontal flight path, and if more power be utilized to drive them they will rise, while if less power be used they will fall to the earth. This feature has great drawbacks, for if we design a speedy machine, we are forced to rise from and land on the earth at high speed, which is objectionable and dangerous necessitating strong and bulky landing chassis, etc., while if we design for a slow speed machine, it is unsafe in the air and at the mercy of varying wind puffs. Again the type having fixed form of camber and fixed angle of incidence is subject to bounding flight in gusty wind, the machine jumping high out of its course, if subjected to a sudden gust of wind, or vice versa, suddenly dropping if the velocity of wind meeting it suddenly lessens.

Means hereinafter described according to the present invention have been devised to overcome the foregoing defects. The system of automatic stability adopted in the present invention is such that the lifting effect on each side of the machine is always instantly automatically balanced, no matter how the wind velocity may vary on the two sides of the machine. There is practically no moment of inertia due to the movable parts of the device controlling the planes, therefore there is no dangerous oscillation set up during operation. Although the pressures on the planes are automatically kept in balance, yet the aviator can if desired instantly take command of the wing warping by simple turning of a hand wheel to right or left as the case may be. Further the same wheel moved up or down may operate the elevating planes, or if moved sideways operate the steering planes or rudders. The ribs of the planes are made flexible, and by means of a lever situated by the side of or within easy reach of the aviator the camber or angle of incidence may be varied as desired, giving a variable speed ratio; within safe limits to the machine. Thus the aeroplane may be given a slow flying speed for getting off the ground or for landing, and may be converted into a high speed machine while in the air. In addition to these advantages the camber and angle of incidence given is actuated through the medium of a spring buffer of predetermined strength, in such manner that if a sudden

gust of wind of increased velocity meets the aeroplane the camber and angle of incidence is automatically reduced until the pressure on the planes balances the resistance of the spring buffer and so prevents the unnerving and dangerous bounding flight in which existing types of machine indulge in gusty weather.

A special feature of the stability control mechanism is its extreme simplicity and its applicability to practically any type of machine, monoplane or biplane.

I will now describe a form of aeroplane constructed according to this invention, or so much thereof as is necessary to render the invention clear.

Figure 1 shows a side elevation of the aeroplane. Fig. 2 is a front elevation in part section. Fig. 3 a partial plan view on a smaller scale, Fig. 3^a is a continuation thereof, and Figs. 4 to 6 show details of the general arrangements and construction of the stability and control mechanism.

In all the views like parts are indicated by like reference letters.

The fuselage in the construction illustrated consists primarily of two long trussed girders X, X arranged about 8 feet apart and parallel to each other, being held together by traverse spars and stays, each girder being fitted with long skid members S. On each skid member is mounted a short axle S' carrying a pair of wheels S'', arranged in similar manner to the wheels on the Farman type of skid. Mounted between the girder skid members is a torpedo shaped body of stream line formation arranged to accommodate the engine, fuel tanks, aviator, passenger, etc.

In the construction illustrated the propeller Y is situated in front of the main plane, while forward and rear elevating planes f and r respectively (Fig. 3 and its continuation Fig. 3^a) are fitted and connected together in such manner as to be operated similarly and simultaneously by the aviator. The rear elevating plane is supplemented by a fixed plane r' bearing no weight, of such area as to give a certain degree of longitudinal stability in a horizontal plane. This supplemental plane is also of such disposition as to insure that, with the engine stopped and with the elevating planes in their mid or central position, the machine will descend at its natural gliding angle when falling.

Directional control in a horizontal plane is effected by two rear vertical planes or rudders v (Figs. 1 and 3) carried at the rear end of the longitudinal skid members at the tail end of the machine, and in order to prevent slewing around of the machine by side gusts and to give assistance in turning, fixed vertical panels or planes U (Fig. 1) are provided at the front ends of the longitudinal skid members.

tudinal members. The relative area of the front and rear vertical planes is such that under the influence of side winds their movements about the center of gravity of the machine balance.

The relative area of the front and rear elevators and their relative interconnected movement is such that their active moments about the center of gravity of the machine balance, thus, during their operation, relieving them of any unnecessary strain of taking any of the dead weight of the machine, and also reducing inertia and momentum effects.

All the weight is grouped as closely as possible around the center of gravity of the machine as a whole, which is also the center of pressure of the main plane, (the front and rear planes carrying no weight), in such manner that the control is as effective and quickly acting as possible and the moment of inertia is a minimum.

The main planes are set with a dihedral angle between them and are constructed in such manner that while possessing great strength and weight carrying capacity they are exceedingly flexible and easy to warp. This feature is accomplished by constructing them each with a forward rigid transverse main spar A, and a rear movable spar B hinged at its inner end to the body at C (Figs. 1 and 2). To these spars are attached upper and lower ribs m, n, forming a double surfaced plane.

The lower ribs are of tapering formation, and are fixed to both spars. The upper ribs are rigidly fixed to the front spar but are slidably attached to the rear movable spar, and are preferably arranged staggered in respect to the lower ribs. The upper and lower ribs are not attached to each other, so that when the planes are warped the upper surface is free to slide slightly in respect to the lower surface, and the lower surface whatever the degree of warping assumes a circular contour in section at all points, giving a very near approximation to a true parabolic grading, and thus insuring that the center of pressure will remain practically immovable in respect to the leading edge, whatever be the variation in curvature, or angle of incidence of the planes.

Outrigger spars D are attached to the skid members projecting out on either side of the body beneath the main plane, to the rigid main spar A of which they are trussed and struttied (Fig. 2) forming a girder-like formation of great strength and lightness.

Cables E attached to suitable points G on the rear movable wing spars B pass around pulleys H, H₁ on the outrigger spars and are connected to the ends of a chain J (Fig. 2) running over a central sprocket wheel K carried in a bearing mounted in a sliding rod L which slides in bearings O carried by

a sliding carriage P which in turn slides upon guide rods T. In the construction shown the carriage P is formed by tubes sliding on fixed rods or frame parts T, but it is to be understood that the invention includes any other suitable form of sliding or adjusting mechanism.

A buffer spring W tends to keep the sprocket wheel K in its normal position, it being of such stiffness that it is just strong enough to take the combined pull on the cables and retain the curvature of the main planes when the machine is in flight.

It will easily be seen that if the pressure on the plane on one side of the machine exceeds the pressure of the plane of the other side, the plane subject to the excess of pressure will flatten out, decreasing its angle of incidence, but in doing so will, through the media of the cables and chain, warp down the plane on the other side, increasing its angle of incidence until the pressure is equally balanced on either side of the machine. Thus an automatic action will take place continuously with every variation of difference of pressure on either side of the machine to balance the machine, and keep it from rolling sidewise. It will be apparent that these movements being very slight, and the weights of the moving parts being very little, inertia effects will be negligible, the large area of the planes easily damping out any tendency to oscillation or to and fro motion of the arrangement. If a sudden excess of pressure obtains simultaneously on the planes on both sides of the machine, the buffer spring gives way, both planes flattening out, reducing their angle of incidence, and consequently the pressure on them, thus preventing bounding flight in gusty winds.

Although as previously described the machine is arranged to be automatically stable in a lateral direction, yet a hand control for the wing warping is provided in such manner, that while with the hand wheel or lever in mid position it in no way interferes with the aforesaid automatic function, command can be instantly taken if necessary or desired.

Figs. 4 to 6 show in detail a general arrangement of the control mechanism. A control column 1 is mounted substantially horizontally and longitudinally in front of the aviator. It is mounted on trunnions 2 on a rotatable cross shaft 3 in such manner that it can be rocked up or down or from side to side. Movement up or down is arranged to operate the elevating planes f, r, while sidewise movement operates the steering rudders v. Mounted rotatably on the column is a hand wheel 4 which controls the manual warping of the planes. It will be apparent that by this arrangement every control movement is absolutely natural and correct, and the machine will follow di-

rectly the movements made on the control column, thus obviating any chances of making mistakes in control operations. The chain sprocket wheel K is connected through the media of bevel wheels 5, 6, telescopic shaft 7, universal joint or couplings 8 and a double-action clutch Z to the hand wheel 4. This clutch Z constitutes a very important feature of the wing warping control mechanism, and is so designed that when the hand wheel is held in its normal or mid position, the clutch is disengaged and the chain sprocket wheel is free from control of the hand wheel and can move in either direction as the difference of pressure on the two sides of the planes varies, but it is further contrived, that if the hand wheel be moved from its said mid position in either direction, the clutch engages, and the wings 20 may be forcibly warped at will.

The clutch is constructed as follows:—The hand wheel is attached to a spindle having formed upon it a steep thread 9 and mounted upon this threaded portion is a nut 10 baying its outer surface in the form of a pair of opposed conical frusta. Surrounding the nut and prevented from longitudinal movement in respect to the hand wheel spindle is a cylindrical portion 12 having its inner surface 30 in the form of a similar pair of opposed conical frusta adapted to engage the surfaces on the periphery of the nut. The cylindrical portion 12 is attached to the control column 25, which through the media of suitable connections is adapted, upon rotation, to transmit motion to the chain sprocket K to warp the wings of the aeroplane. The conical portions on the cylindrical part 12 are arranged to be normally 40 free of the conical portions on the nut 10 when the hand wheel is in its mid position, but if the hand wheel be moved to either right or left the nut 10, traveling along the threaded portion of the spindle, comes into engagement with the cylindrical part 12 and the movement of the hand wheel is consequently transmitted through the coupling 8 and bevel gearing to the chain sprocket K to warp the planes.

In order that the aviator may if desired vary the flying speed of the aeroplane, means are provided for varying the normal camber and angle of incidence of the main planes. The carriage P upon which is slidably 55 mounted the sprocket wheel K and its buffer spring W, is in turn slidably mounted on the rods T, T which form part of the aeroplane fuselage, and is arranged to be moved to, and locked in any position in its travel 60 by means of the hand lever 13, working in a quadrant 11, suitably disposed conveniently to the aviator. Therefore by raising the lever 13, which is pivoted at 15, the carriage comprising the bearings O and tubes P 65 carrying the sprocket wheel K and the in-

ner member of the telescopic shaft 7 with its bevel gearing, will be forced down, thus slackening the cables E. The aviator can, therefore, from his seat vary the camber or angle of incidence of the main planes without in certain predetermined limits. It is possible therefore by these means to start from and land on the ground at a comparatively slow flying speed, but while in the air vary the speed to one's liking.

It may be remarked that whatever the flying speed of the machine, the weight being constant, the lifting pressure on the planes must be constant for a horizontal flight path. It should therefore be noted that in the device described for varying the angle of incidence of the planes, the buffer spring being moved bodily with its abutments, its predetermined adjustment is not upset whatever variation be made to the normal angle of incidence.

In order to equalize the head resistance when the normal head resistance on one side is reduced and on the other side increased on the planes being warped, I preferably provide means for producing an auxiliary equalizing head resistance, these means being brought into play automatically or manually. This auxiliary head resistance may be produced by means of an auxiliary rudder or surface in the central longitudinal plane of the machine, or by means of a flap or flaps or an extending surface on each plane so as to be brought into play to set up an equalizing head resistance.

I may conveniently employ the auxiliary rudder or surface or the gear employed for producing the stabilizing action of the planes, so that as the planes are warped and the head resistance varied on the two sides, the equalizing rudder or surface is caused to set up an equalizing resistance.

While I have referred to a rudder it is obvious that the equalizing plane may be arranged either in front or in rear of the main planes or wings.

As previously stated the main planes are set with a dihedral angle between them, although means are described for insuring automatic lateral stability. This combination is employed for the purpose of insuring that the aeroplane in making turns will automatically adjust itself to the correct banking tilt according to the radius of the curve made and the flight speed. If the dihedral arrangement were not used, the machine, owing to the very fact of its automatic balance of pressure on its wings, would take a turn on a perfectly even keel, and would in consequence, owing to centrifugal force, drift out sidewise from its course. The use of the dihedral disposition prevents this action, the sidewise drift causing a tilting the machine toward the center of the curve until the resultant pressure on the planes is in

line and balances the resultant of the forces of centrifugal force and gravity while the automatic action of the wings to adjust themselves to balance the pressure obtaining on either side of the machine will make compensation for the faster velocity of the outer wing. It is therefore possible with perfect safety to make turns of any description with the knowledge that the machine will automatically adjust itself to the exact banking tilt required.

It is obvious that various modifications may be made in the manner of carrying the various features of this invention into effect, 15 those described above being given merely by way of example.

What I claim and desire to secure by Letters Patent is:—

1. An aeroplane having the two sides of its 20 plane so constructed and provided with connecting means that an excess of air pressure on one side will produce automatically a stabilizing action on the other side, comprising a hand control wheel, a control shaft detachably secured to the hand wheel, gearing between the control shaft and the connecting means, and a clutch for automatically locking the shaft to the hand wheel when the latter is rotated from its 30 neutral position, substantially as set forth.

2. Stabilizing means for aeroplanes comprising rear stays hinged to the body of the machine, warping cords attached at one end to said stays at equal distances from the 35 center of pressure, a chain connecting the other ends of said cords, a sprocket wheel engaged by said chain, a control shaft, means for connecting the control shaft to the sprocket wheels, a hand wheel, and 40 means for automatically locking said hand wheel to the control shaft when the hand wheel is turned from its neutral position.

3. An aeroplane having the two sides of its plane so constructed and provided with 45 connecting means that an excess of air pressure on one side will produce automatically a stabilizing action on the other side comprising a hand control wheel, a shaft detachably secured to the hand wheel gearing 50 between the shaft and the connecting means, means for connecting the shaft to the hand wheel only when the latter is rotated from its neutral position.

4. In an aeroplane a cord connecting the 55 outer ends of the plane together, a pulley over which said cord passes, a hand operated control which when at or near its mid-position allows the pulley freedom to act automatically, but when moved in either direction from the mid-position engages with and controls the said pulley.

5. In an aeroplane a cord connecting the outer ends of the plane together, a pulley over which said cord passes, a tubular carriage for said pulley, a spring acting to 65 maintain said carriage in its normal place, a hand operated control which when at or near its mid-position allows the pulley freedom to act automatically, but when moved in either direction from the mid-position 70 engages with and controls the said pulley.

6. In an aeroplane, a cord connecting the outer ends of the plane together, a pulley over which said cord passes, a tubular carriage for said pulley, a second sliding carriage adapted to be moved and held or locked in any desired position, a hand operated control which when at or near its mid-position allows the pulley freedom to act automatically, but when moved in either 80 direction from the mid-position engages with and controls the said pulley.

7. An aeroplane having a controlling hand wheel, a column operated thereby, a double cone clutch for connecting the hand 85 wheel to the column only when the hand wheel is rotated, a universal joint for said column, and control devices for the planes, operated by moving said column about its universal or rocking joint. 90

8. An aeroplane control mechanism comprising a cord connecting the two outer sides of the plane, a pulley over which said cord passes, in combination with a hand wheel, a column attached to said hand 95 wheel, transmission means intermediate the column and pulley, and means for normally holding said hand wheel out of operative connection with the column and of automatically locking it thereto when the handle 100 is rotated in either direction from its mid-position.

9. In a plane controlling device for aeroplanes, a hand wheel, a shaft fixed thereto, a control shaft, a clutch device between the 105 hand wheel shaft and the control shaft consisting of a screw thread on the hand wheel shaft, a nut internally screw-threaded to engage the screw threaded portion of the hand wheel shaft and having a pair of opposed conical outer surfaces and a correspondingly shaped member surrounding said nut and connected to the control shaft, substantially as set forth. 110

In testimony whereof I have affixed my 115 signature in presence of two witnesses.

BELTON T. HAMILTON.
